FAN TYPE HEATER

Caryl A. Lindberg, Glendale, and Howard W. Eckles, St. Louis, Mo., assignors to The Emerson Electric Manufacturing Company, St. Louis, Mo., a corporation of Missouri

Application October 13, 1945, Serial No. 622,218

26 Claims. (Cl. 219—39)

1

The present invention relates to a fan type heater, and particularly to a fan type heater having electric heating units in combination with a fan for blowing air thereover, especially where the heating units are of the radiant type.

It is an object of the invention to provide such a heater having a plurality of heating units separated by air flow passages through which air may be discharged by means of a fan and, at the same time, heated.

A further object is to provide individual radiant heating units having characteristics providing for good radiation of heat and good conduction of heat into the air directed thereover.

A further object is to provide a heater of this kind in which the heat not discharged outwardly from the heater is restricted in its flow toward the top of the casing, whereby the casing is prevented from over-heating.

A further object is to provide a casing for such a heater, and especially one into which the various elements may be quickly and easily assembled or replaced.

More particularly, it is an object of the invention to provide a heater having a base and a casing rockable thereon, the casing being formed of two hollow sections joined together about substantially a medial plane, with a duct formed in the front casing section and removably supporting the heating elements, reflectors therefor, and a blower or fan, whereby, when the sections are separated, the operating parts will be conveniently accessible for assembly and disassembly.

A further object is to provide a heater having a casing angularly adjustable on a base member with a particularly easily constructed and operated attachment between the two.

A further object is to provide a handle means having a particular location for most convenient carrying of the heater, and to prevent the heater being placed against a vertical surface in such a manner as to restrict flow of air into fan or blower.

Other objects will appear from the accompanying drawings and ensuing description wherein:

Fig. 1 is a front elevation of the heater;

Fig. 2 is a side elevation of the heater, taken on the left of Fig. 1;

Fig. 3 is a rear elevation of the heater, partly broken away;

Fig. 4 is a medial front-to-rear vertical section through the heater, taken on the line 4—4 of Fig. 1;

Fig. 5 is a medial horizontal section, taken substantially on the line 5—5 of Fig. 1 and the line 5—5 of Fig. 4;

2

Fig. 6 is a partial vertical section of the lower part of the heater casing, looking from rear to front, taken on the line 6—6 of Fig. 4;

Fig. 7 is a horizontal section showing a fragment of the upper concave surface of the base, taken on the curved line 7—7 near the bottom of Fig. 4;

Fig. 8 is a plan view of the base section alone;

Fig. 9 is a plan view of one end of one of the reflectors;

Fig. 10 is a front elevation of one end of one of the reflectors;

Fig. 11 is an elevation of one of the casing supporting trunnions;

Fig. 12 is an elevation of one of the outer asbestos side insulators;

Fig. 13 is an inside elevation of one of the inner asbestos side insulators;

Fig. 14 is a view from the opposite side of Fig. 13 of an inner asbestos insulator;

Fig. 15 is a fragmentary section of the attaching strip between the casing sections, taken on the line 15—15 at the left edge of Fig. 6; and

Fig. 16 is a separated view of the center of the upper part of the casing sections, looking down at the top center of Fig. 4.

The heater, generally indicated at 20, includes a hollow base 21 and a hollow, two-section casing 22 mounted on the base for a certain rocking movement, as will appear.

The base 21 has a concave upper surface 23. This surface 23 has two symmetrical openings 24 and 25 therein (Fig. 8). The outer ends of the openings 24 and 25 have upstruck flanges 26 and 27, respectively. Also, the openings 24 and 25, at their inner edges, have downturned flanges 28 and 29. (An opening in the bottom wall of the base is not to be confused in Fig. 8 with these downturned flanges 28 and 29).

The two openings in the upper concave surface 23 of the base provide between them a bridge wall 30 which has a transverse slot 31 therein.

The base is hollow, being preferably made from sheet metal. It has a bottom wall 34 with an opening 35, already parenthetically mentioned, disposed opposite the slot 31 for purposes of assembly, as will be shown.

Two opposite trunnions 38 and 39 are secured by the base to support the casing. Each of these trunnions has a lower offset portion 40 welded to the inner respective side wall of the base, and the main body of each trunnion extends upwardly through the respective opening 24 or 25 and is secured to the adjacent upstruck flanges 26 and 27 of the upper concave wall 23 of the base. The

two unions between each trunnion and the base may be made by welding. The trunnion 38 is provided with a substantially semi-circular socket 42 at its upper end, and the trunnion 39 is provided with a similar socket 43, these sockets 42 and 43 being formed by flanges turned out to provide bearing surfaces, as appear in Figs. 5 and 11.

The casing 22 consists primarily of a front section 50 and a rear section 51, preferably substantially symmetrical, joined substantially along a medial, vertical, side to side plane. Each of the front and rear sections has an outturned abutment flange. The section 50 has the abutment flange 52, and the section 51 has the abutment flange 53. At spaced intervals along the sides, the abutment flanges have flared projections 54 and 55, respectively, to receive a channel-shaped attachment strip 56, which thereby is held in place and cooperates to secure the two sections 50 and 51 together. At the top of the two casing elements, the abutment flanges 52 and 53 have no flared portions, and consequently the strip may be inserted by moving its ends downwardly from the top over the spaced outturned flanges 55. However, at the center of the top, there arelapping tongues 58 and 59, shown separated in Fig. 16 and together in Fig. 4. The tongue 59 on the section 51 is offset to provide smooth outer contour to the overall casing. It is also threaded to receive a screw 60 which passes through a hole in the tongue 58.

The bottom of the casing sections are convex concentrically with the concave surface 23 of the base, both arcs being struck about the center of the trunnion openings 42 and 43. The adjacent edges of the bottoms of the two casing sections 50 and 51 are provided with a series of flanges. The casing section 50 has outer downturned flanges 62 and 63 abutting corresponding flanges on the back section 51, the flanges being joined by pins or screws 64 and 65, respectively. These flanges extend into the openings 24 and 25 of the base. The lower edges of the casing section 50 are also provided with inner abutment flanges 66 and 67 adapted to abut corresponding flanges on the rear section 51, these flanges likewise being disposed in the base openings 24 and 25.

Centrally, the casing section 50 is provided with a depending flange 70, and the rear casing section 51 with a corresponding flange 71. These flanges extend into the slot 31 of the base, and receive a friction leaf spring 72, the limits of which extend beyond the slot 31 and are confined between the two flanges 28 and 29 on the portion 30 of the base (Figs. 4, 6, 7). The spring 72 is confined by a cotter pin 73 beneath it and passing through the flanges 70 and 71.

As will later appear, the upper casing 22 may pivot about the centers of the trunnions 42 and 43 with the convex bottom of the casing 22 moving within the concave upper surface 23 of the base. To permit this, the slot 31, centrally of the base, accommodates the two flanges 70 and 71, and the openings 24 and 25 accommodate the other depending flanges. The two casing sections 50 and 51 have in their bottom convex walls corresponding notches providing slots 75 and 76 to accommodate the trunnions 38 and 39, respectively, which are attached and project rigidly upward from the base.

The front casing section 50 has spot-welded thereto trunnion hubs or bearings 80 and 81. These trunnion hubs are generally cup-shaped, as appear in Fig. 5, and have bearing surfaces that are cradled within the semi-circular bear-

ings 42 and 43 of the trunnions 38 and 39. By this means, the front casing section 50 and all of the associated parts, including the back section 51, are supported on the base. They may be lifted from the base only by removal of the cotter pin 73 and the spring 72. With these parts removed, the whole upper casing 22 may be lifted out of the trunnions.

The front section 50 likewise supports the heating and fan elements. The front section has a large opening 83 in it. Part of the metal from this opening is bent backwardly horizontally at 84, then downwardly at 85, and backwardly at 86. It will be seen, by reference to Fig. 6, that the section 85 tapers inwardly downwardly. The flange 86 is secured, as by spot welding, to the inner surface of the bottom of the front section 50 of the casing. This bent portion provides a support for the fan and heater elements.

Additionally, there is a generally U-shaped member projecting upwardly from the horizontal portion 84 to provide side walls and a top wall for the heater and blower mechanisms. This member, which may be generally designated 87, has two side walls 89 and 90, which have inturned bottom flanges 91 and 92, respectively, welded to the bottom of the section 84 of the member 87. The side walls likewise have inturned flanges 94 and 95, respectively, secured to the walls of the front casing section 50 about the opening 83.

The top wall 97 of the U-shaped member has an upturned front flange 98 that is united with the edge forming the upper part of the front opening 83. It will be seen, therefore, that the horizontal portion 84, with the two side walls 89 and 90 of the U-shaped member and the top wall 97 thereof, form a duct, open at the front through the opening 83, and open at its back at approximately the back of the front section 50 of the casing 22. The two side walls 89 and 90 are lined first with heat and electric insulators in the form of asbestos liners 101 and 102, the shape of which is shown in Fig. 12. These liners extend from the back edge of each of the walls 89 and 90 forwardly to adjacent the inturned flanges 94 and 95. Additionally, there are two inner asbestos insulators 103 and 104. Figs. 13 and 14 show the configuration of the liner 103, Fig. 13 being the inner surface thereof, and Fig. 14 being the outer surface. The two liners at each side wall are fastened to their respective side walls by means of screws 105 passing through openings in the asbestos members and the side walls.

Referring to Figs. 13 and 14 for the details of the inner asbestos liners, it may be seen that there is a series of vertically spaced openings 106 that are formed as circular enlargements in slots cut in from the forward edge of the member. The front slot portions are indicated at 107. The upper opening 106 has a backwardly extending slot 108, as does the bottom one. Additionally, each of the slots 107 is flanked by an upper notch 109 and a lower notch 110. Each opening 106 has backwardly spaced therefrom a small hole 111. As will hereafter appear, these notches 109 and 110, with the holes 111, support reflectors for radiant heater supports mounted within the holes 106.

Two arcuate notches 112 and 113 intersect each other at the bottom of the back edge of the member 103, and have notches 114 and 114' extending forwardly therefrom.

Into the outer surface of the member 103 are cut two vertical grooves 115 and 115' to receive and to insulate leads for the several coils. These

two grooves are closed by the abutting surfaces of the asbestos liners.

The views show the asbestos liners in position and secured to the side walls 89 and 90. Heating coil supports 116, 117, 118, and 119 are supported at their ends in the openings 106, and they receive heating coils 120, 121, 122 and 123, respectively. These coils are wired from terminals 126 and 127 secured in openings within the two outer liners 101 and 102, the same being thereby insulated from each other. A wire 128 extends from the terminal 126 in the slot 114' to the groove 115, thence upwardly to the back notch 108 of the support 116. It passes through this notch and is wound about the support 116 to form the heating coil 120. At the other end of the support 116 it passes through the notch 107 into the other groove 115' and upwardly to connect with the coil 121 in similar fashion. The open end of the top coil 123 passes through the top notch 108 to the groove 115', and thence back to the upper slot 114 and to the other terminal 127.

Each heating coil is disposed within a reflector 130. All of these reflectors are identical. They are generally U-shaped in cross section with relatively horizontal outer edges 131 and 132 top and bottom, merging by smooth curves into sloping upper and lower inner surfaces 133 and 134, these two surfaces being joined by an arcuate back wall 135, the back wall being concentric with the centers of the heater supports 116, etc.

The inner surfaces of these reflectors are preferably highly polished and plated.

At their ends, the reflectors are provided with upper and lower projections 138 and 139. Their back surfaces likewise have projections 140. The reflectors are supported in the inner asbestos liners by having their upper and lower projections 138 disposed within the upper and lower flanking notches 109 and 110, respectively, and with their center projections 140 disposed within the holes 111. It will be seen that the several reflectors are separated to provide air flow passages between them and above the topmost one and the top surface 87 of the U-shaped supporting member.

A fan and motor are mounted back of the reflectors. To this end, a fan supporting beam 144, of the longitudinal shape shown in Fig. 4, is provided. It is of channel-shaped cross section. Its lower end is attached by a screw 145 with the vertical portion 85 duct support. Its upper end overlies the top part 97 of the U-shaped support and is bolted thereto at 146. A fan motor 147 is secured to the frame 144 and supports the fan blade assembly 148 which fits adjacent the duct aforementioned and also close behind the reflectors. The back wall of the back casing member 51 is provided with a plurality of openings 150 to supply air to the fan. The back casing member likewise has a handle 151 disposed at the upper corner thereof. It provides a means for lifting the heater, which is out of sight from the front, and which is away from the hotter parts of the casing, and which gives a good balance point for carrying the heater.

The wiring of the heater includes a cable 155 brought into the hollow base through the back thereof to a switch 156 mounted at the front and providing an accessible switch button 157. From this switch, two cables extend upward through the opening 25 of the base. The first such cable 158 passes through a hole in the flange 86, and is supported in the channel-shaped motor supporting bracket 144 to provide leads to the motor.

The other cable 160 carries two wires leading to the two terminals 126 and 127. The switch preferably turns on both the fan and the heaters at once.

5 A guard grill 165 is disposed over the front opening in the heater. It is here shown as consisting of a plurality of rods 165 welded together with a lower transverse rod 166 forming a stop means with the bottom ends 167 of the vertical rods. These ends 167 are slipped down through openings 168 in a horizontal member 84 with the bottom horizontal rod 166 acting as a ledge. The upper ends of the vertical rods are threaded at 169 and extend through the upper part of the casing member 50 until the top transverse rod 170 strikes the latter. Nuts 171 clamp a bracket 172 against the front of the casing and the flange 88 to hold the grill removably in place.

Assembly and operation

20 The construction of this heater is such that it can be readily assembled by line production methods which are relatively inexpensive. It also can be disassembled for repair purposes.

25 In any assembly operation, the base 21 will have the switch 156 attached thereto, and the electrical leads disposed therein. The front casing element 50 will have all of the mechanism ultimately secured to it.

30 The assembly of the mechanism on the front casing section is accomplished by first installing the two outer asbestos liners 101 and 102. The two opposite inner liners, with the heater supports, heaters, wires and reflectors, in proper positions, are then inserted. The screws 105 are fastened to secure these various elements together and to the supporting framework. The leads 125 and 128, as well as the lines from the switch in the base, are connected to the terminals 126 and 127. Thereafter, the motor may be installed, it having previously been mounted on the bracket 144, by fastening the screws 145 and 146 to hold the bracket 144 to the frame.

35 Thereafter, the two casing members 50 and 51 are brought together to have their abutment flanges against each other.

40 Screws 64 and 65 are passed through the flanges 62 and 63, respectively, of the two front and rear casing members. The screw 60 is installed at the top through the elements 58 and 59. The two flanges 70 and 71 are disposed through the metal slot 31 of the base where they are accessible through the opening 35 in the bottom of the base. The spring 72 is disposed over the flanges 70 and 71 and held in place by the pin 73. Then the trim strip 56 is slipped down from the top over the flaring flanges 54 and 55 disposed at intervals along both side edges, this completing the assembly.

45 It is clear that the angular position of the casing 22 may be varied by simply rocking the casing about the trunnions 38 and 39. The spring 72 permits this rocking to take place against friction, which will hold it in adjusted position.

50 65 What is claimed is:

60 1. In a heater, a framework, opposite insulating means removably secured at the sides of the framework, and having cutout portions therein, a heater support extending between the two insulating means and secured by disposition in cut-outs therein, a reflector open at the front and extending around the heater support, said reflector extending between the two insulating means and secured by disposition in cut-outs 65 70 75 therein, a blower removably attached to said

framework, and a hollow casing to enclose the framework, having a first section supporting the framework and a closure section removably attached to the first section.

2. In a heater, a base, a two section casing rockably mounted on the base, said sections comprising a front section and a rear section, both hollow, substantially symmetrical, and joinable about a middle line of the heater, said two sections being removably attached together, a framework in the first section, heating means removably secured to the framework, a blower removably secured to the framework, whereby, when the second section is removed, the mechanism will be contained in the first section, and a handle disposed at the upper rear corner of the rear section.

3. In a heater, a base having a concave, arcuate, surface thereon, a casing supported on the base for rocking about the center of said arcuate surface, said casing being in two sections, said sections having cooperating flanges adapted to abut each other to form ears that project through the arcuate surface of the base, a slot in the arcuate surface to receive said ears and permit limited rocking movement thereof, and of the casing, and frictional means interengaging between the ears and the base adjacent thereto, to restrict said rocking movement.

4. In a heater, a base having a concave, arcuate surface thereon, a casing supported on the base for rocking about the center of said arcuate surface, said casing being in two sections, said sections having cooperating flanges adapted to abut each other to form ears that project through the arcuate surface of the base, a slot in the arcuate surface to receive said ears and permit limited rocking movement thereof, and of the casing, upwardly open trunnions extending upwardly from the base and into the casing, and bearings in the casing and rockable in the trunnions about the center of said arcuate surface of the base, and means to hold the bearings in the trunnions.

5. In a heater, a base having a concave, arcuate surface thereon, a casing supported on the base for rocking about the center of said arcuate surface, said casing being in two sections, said sections having cooperating flanges adapted to abut each other and form ears that project through the arcuate surface of the base, a slot in the arcuate surface to receive said ears and permit limited rocking movement thereof, and of the casing upwardly open trunnions extending upwardly from the base and into the casing, and bearings in the casing and rockable in the trunnions about the center of said arcuate surface of the base, said bearings being wholly mounted on one section of the casing.

6. In a heater, a base having an arcuate upper surface thereon, a pair of upwardly open trunnions extending upwardly from opposite sides of the base, and having bearing cradles concentric with the arcuate surface, a casing having a front hollow section and a rear hollow section joined together substantially along a medial line, bearings secured to the inside of the front section and rockable in the trunnions, said casing sections having openings to receive the trunnions and permit the rocking, heating means removably supported on the front section, and accessible by removal of the rear section, and a blower removably supported on the front section and accessible by removal of the rear section.

7. In a heater, a base having a pair of upwardly open trunnions upstanding therefrom, a casing formed of two hollow sections, one a front and the other a rear section, means removably holding the two sections together, a pair of bearings on the inner surface of the casing fittable downwardly into the trunnions, a projection and slot arrangement between the base and the casing, and removable friction means attached with said arrangement to maintain the bearings in the trunnions and frictionally resist rocking movement of the casing relatively to the base.

8. In a heater, a base having a pair of upwardly open trunnions upstanding therefrom, a casing formed of two hollow sections, one a front and the other a rear section, means removably holding the two sections together, a pair of bearings on the inner surface of the casing fittable downwardly into the trunnions, a projection and slot arrangement between the base and the casing, and removable friction means attached with said arrangement to maintain the bearings in the trunnions and frictionally resist rocking movement of the casing relatively to the base, the projection and slot arrangement comprising a flange on the casing projecting through a slot in the upper base wall, a spring friction device connected with the flange and engaging the base wall adjacent the slot, the said base wall being arcuate.

9. In a heater, a base having a pair of upwardly open trunnions upstanding therefrom, a casing formed of two hollow sections, one a front and the other a rear section, means removably holding the two sections together, a pair of bearings on the inner surface of the casing fittable downwardly into the trunnions, a projection and slot arrangement between the base and the casing, and removable friction means attached with said arrangement to maintain the bearings in the trunnions and frictionally resist rocking movement of the casing relatively to the base, the projection and slot arrangement comprising a flange on the casing projecting through a slot in the upper base wall, a spring friction device connected with the flange and engaging the base wall adjacent the slot, the said base wall being arcuate, the casing having an arcuate bottom with slots therein to accommodate the trunnions.

10. In a heater, a base, a casing comprising a pair of hollow sheet-like casing sections having abutting edges at the top and sides, interengaging attachment means at the top of the casing to hold the sections together, the abutting edges of the casing sections at the sides having outwarded flanges, and a connecting strip having inturned flanges engageable over the outwarded flanges for attaching the casing sections together for ready separation, means pivotally supporting the casing on the base, and heating means mounted in the casing.

11. In a heater, a sheet material casing section having an air opening therethrough, material from the opening being bent backwardly therefrom at the bottom edge thereof, and downturned at its back and attached to the inside of the bottom surface of the casing, sheet material side and top walls connected with the backwardly bent material and forming therewith a duct, heating means mounted within the duct, and a blower attached to the duct.

12. In a heater, a sheet material casing section having an air opening therethrough, material from the opening being bent backwardly there-

from at the bottom edge thereof, and downturned at its back and attached to the inside of the bottom surface of the casing, sheet material side and top walls connected with the backwardly bent material and forming therewith a duct, heating means mounted within the duct, and a blower attached to the duct, there being heat and electrically insulating liners for the side walls of the duct, a plurality of heating elements extending across from one liner to the other, a reflector device for each heating element, the reflector devices being spaced apart to provide air flow therebetween.

13. In an electric heater, a casing, an air flow duct in the casing having inlet means, an air outlet for discharge of heated air, and a blower to cause air to flow through the duct and out the outlet, an elongated heating element supported on the casing within the duct, and having radiant heating coil means with a front part disposed opposite the outlet to deliver heat radiantly directly outward therethrough, and having other parts disposed to discharge radiant heat within the casing, an elongated reflector substantially co-extensive with the elongated heating element, the reflector having an inner reflecting surface that extends in a curve around the back part of the heating element opposite the outlet, and in spaced relation thereto, and the reflector having inner side surfaces that extend toward the outlet from the back surface, in spaced relation to the side parts of the heating element, and terminating in forward edges spaced from the heating element and extending forwardly to permit free passage of radiant heat out the outlet from the front part of the heating element, and by reflection from the other parts of the heating element, the outer surface of the reflector being curved on its back side, and extending forward at its sides toward the outlet, and terminating in forwardly extending edges joined with the forward edges of the inner surfaces, and the reflector having its outer surface shaped, as aforesaid, to permit flow of the air against the back of the reflector, and around its sides, the forward edges of the reflector extending substantially in the direction of flow of said air moved through the duct by the blower, and means in the air flow duct adjacent to but spaced from the reflector, said means also having forwardly extending edges spaced a substantial distance from the forward edges of the reflector, the adjacent means and the reflector thus providing air flow passage means with its forward surfaces extending forwardly to cause air to discharge from the outlet directly forwardly in substantially the same direction as radiant heat from the front part of the heating element.

14. In an electric heater, a casing, an air flow duct in the casing having an inlet, a forward outlet for discharge of heated air, and a blower to cause air to flow through the duct and out the outlet, a plurality of elongated heating elements each extending across the duct and supported at its ends, the elements being between the inlet and the outlet, each heating element comprising coil means with forward parts disposed to discharge radiant heat out the outlet, and other parts radiating heat toward the inside of the casing, a plurality of elongated, heat conducting reflectors, one for each heating element, all being disposed across the air duct between the heating elements and the inlet, each having an inner curved surface back of its heating element to reflect heat from the coil for-

wardly, and to be heated by the coil, and having forwardly extending inner side surfaces that are spaced from the coil and project forwardly toward the opening therefrom, and terminate in edges spaced from the coil on opposite sides thereof, whereby direct and reflected radiant heat from the coils may emit from the outlet, each reflector having an outer surface that is curved on its back toward the inlet, and extends around the sides and forwardly to join the forward edges of the inner surfaces, the forward parts of the outer surfaces extending to said edges substantially forwardly, and forward edges of adjacent reflectors being spaced and shaped to provide air flow channels that extend through from behind to forwardly of the heating elements to direct air forwardly out the outlet of the casing substantially in the direction of radiant heat emitted from the outlet.

15. In a heater, a casing, a pair of opposite walls therein formed of insulating material, an elongated heating element extending across between said walls, said walls having recesses to receive the ends of the heating element and support the same, a reflector for disposition around the heating element, the reflector comprising a channel-shaped member with its open side provided for delivery of radiant heat from the element, the two walls having recesses spaced from the recesses for the heating element, and the reflector having extensions interfitted into said spaced recesses for supporting the ends of the reflector in said walls.

16. In a heater, a casing, a pair of opposite walls therein formed of insulating material, an elongated heating element extending across between said walls, said walls having recesses to receive the ends of the heating element and support the same, a reflector for disposition around the heating element, the reflector comprising a channel-shaped member with its open side provided for delivery of radiant heat from the element, the two walls having recesses spaced from the recesses for the heating element, and the reflector having extensions interfitted into said spaced recesses for supporting the ends of the reflector in said walls, said heating element recesses and the reflector recesses extending through said walls, and additional panels of insulating material outside said walls and contiguous thereto to close said recesses.

17. In a heater, a casing, a pair of opposite walls therein formed of insulating material, an elongated heating element extending across between said walls, said walls having recesses to receive the ends of the heating element and support the same, a reflector for disposition around the heating element, the reflector comprising a channel-shaped member with its open side provided for delivery of radiant heat from the element, the two walls having recesses spaced from the recesses for the heating element, and the reflector having extensions interfitted into said spaced recesses for supporting the ends of the reflector in said walls, said heating element recesses and the reflector recesses extending through said walls, and additional panels of insulating material outside said walls and contiguous thereto to close said recesses, and wiring grooves in an interface of one of said contiguous insulating elements, to receive wiring for the heating element.

18. In a heater, a casing through which air may be drawn, opposite insulative side panels, support means in the casing to hold the walls,

including lateral supports against which the insulative side walls may be removably engaged and held, heating means supported between the insulative panels, and reflector means adjacent the heating means and removably supported between the panels, one of said last named two means having abutment means at its ends, engageable with the panels, to hold the panels separated against the lateral supports, the panels, heating means, and reflector means being slidable from the support means.

19. In a heater, a casing through which air may be drawn, opposite insulative side panels, support means in the casing to hold the walls, including lateral supports against which the insulative side walls may be removably engaged and held, heating means supported between the insulative panels, and reflector means adjacent the heating means and removably supported between the panels, the reflector means having a length to fit between the insulative panels when both are against their lateral supports, and having lug-type interengaging means with the panels and end parts engageable with the panels to hold the panels in spaced relationship and against the lateral supports.

20. In a heater, a casing through which air may be drawn, opposite insulative side panels, support means in the casing to hold the walls, including lateral supports against which the insulative side walls may be removably engaged and held, heating means supported between the insulative panels, and reflector means adjacent the heating means and removably supported between the panels, the reflector means having a length to fit between the insulative panels when both are against their lateral supports and having lug-type interengaging means with the panels and end parts engageable with the panels to hold the panels in spaced relationship and against the lateral supports, the support means in the casing comprising walls forming a duct having an outlet, the panels, heating means and reflectors being slidable into the duct toward the outlet, and stop means adjacent the outlet against which the panels may be positioned.

21. In a heater, a casing through which air may be drawn, opposite insulative side panels, support means in the casing to hold the walls, including lateral supports against which the insulative side walls may be removably engaged and held, heating means supported between the insulative panels, and reflector means adjacent the heating means and removably supported between the panels, the reflector means having a length to fit between the insulative panels when both are against their lateral supports, and having lug-type interengaging means with the panels and end parts engageable with the panels to hold the panels in spaced relationship and against the lateral supports, the support means in the casing comprising walls forming a duct having an outlet, the panels, heating means and reflectors being slidable into the duct toward the outlet, and stop means adjacent the outlet against which the panels may be positioned, the casing having a forward section and a rearward section, the support means and parts thereon supported being in the forward section, and a blower attached to the forward section, removably, behind the reflector means.

22. In a device of the kind described, a hollow casing, a base therefor, upwardly open trunnions upstanding from the base, the casing having bottom opening means to receive the

trunnions within the hollow casing, bearing means in the casing engageable with the trunnions when the casing is lowered onto the trunnions for rocking of the casing on the base, and means to hold the casing against removal from the base, outlet means in the casing, and heater means in the casing for delivery of heat from the outlet.

23. In a device of the kind described, a hollow casing, a base therefor, upwardly open trunnions upstanding from the base, the casing having bottom opening means to receive the trunnions within the hollow casing, bearing means in the casing engageable with the trunnions when the casing is lowered onto the trunnions for rocking of the casing on the base, and means to hold the casing against removal from the base, outlet means in the casing, air inlet means to the casing, and air blowing means mounted on the casing to draw air into the inlet means and out the outlet means.

24. In a device of the kind described, a hollow casing, a base therefor, upwardly open trunnions upstanding from the base, the casing having bottom opening means to receive the trunnions within the hollow casing, bearing means in the casing engageable with the trunnions when the casing is lowered onto the trunnions for rocking of the casing on the base, and means to hold the casing against removal from the base, outlet means in the casing, the means to hold the casing on the base including frictional interengaging means between the casing and the base to restrict rocking movement of the casing.

25. In a device of the kind described, a base member, a hollow casing member, upwardly open trunnions on the base member upstanding into the casing member, bearing means on the casing member engageable onto the trunnions when the casing member is lowered toward the base member, one of said two members having an arcuate surface adjacent the other member, with an opening through said surface, the other member having a projection through said opening adjacent the arcuate surface beside the opening, and frictional means on the projection overlying the arcuate surface to engage the surface and restrict rocking of the casing on the base member.

26. In a device of the kind described, a base member, a hollow casing member, upwardly open trunnions on the base member upstanding into the casing member, bearing means on the casing member engageable onto the trunnions when the casing member is lowered toward the base member, one of said two members having an arcuate surface adjacent the other member, with an opening through said surface, the other member having a projection through said opening adjacent the arcuate surface beside the opening, and frictional means on the projection overlying the arcuate surface to engage the surface and restrict rocking of the casing on the base member, the arcuate surface being on the base member and the projection being on the casing member, and means removably attaching the frictional means to the projection, whereby the casing may be lifted from the trunnions.

CARYL A. LINDBERG.
HOWARD W. ECKLES.
